MANGLE

Harry W. Albright, Blue Island, Ill.

Application November 16, 1935, Serial No. 50,136

3 Claims. (Cl. 38—14)

This invention relates to mangles or ironing machines and more particularly to that type used in commercial laundering establishments where a large quantity of ironing is done and where steam and compressed air supplies are available.

The principal object of the invention is to remove the steam generated in the damp material being ironed as soon as it is generated and while the material is being ironed in the machine.

Another object is to thoroughly dry the ironed material after the material passes from the principal ironing operation of the machine and before the material leaves the machine.

A further object is to preheat the damp material to be ironed to thereby drive off excess moisture before the material passes into the principal ironing operation of the machine.

And a still further object is to apply ironing pressure of the ironing rollers upon the ironing shoes when the machine is in operation and to relieve the pressure and remove the rollers from engagement with the ironing shoes when the machine is not in operation.

In the accompanying drawing illustrating the invention in a selected embodiment

Fig. 1 is a side elevation showing parts thereof broken away;

Fig. 2 is a top plan view showing a part thereof broken away;

Fig. 3 is a detail sectional view of one of the ironing rollers;

Fig. 4 is a detail sectional view of one of the piston chambers used in applying and relieving ironing pressure of the rollers on the shoes; and

Fig. 5 is a detail sectional view of the air valve.

Referring to the drawing, a main frame 6 has a main ironing shoe 7 rigidly mounted therein. The ironing shoe has a large steam chamber 8 therein which extends from the front end of the shoe preferably about two-thirds the distance to the other end. A smaller steam chamber 9 is located in the rear end of the shoe. A suction chamber 10 is provided near the front end of the shoe and preferably about one-third the distance to the rear end thereof, and another suction chamber 11 is provided between the steam chambers 8 and 9. The suction chamber 10 is perforated in its face at 10' which is coincidental with the face of the shoe and its depth is less than the thickness of the shoe so that the steam chamber 8 surrounds three sides of the suction chamber 10. The suction chamber 11 is perforated in its face 11' which is coincidental with the face of the shoe and is also perforated in its back at 11" which is coincidental with the back

of the shoe. The steam chambers 8 and 9 are connected to a suitable source of steam supply by the valved pipe 12. A main ironing roller 13 is journaled in blocks 14 at either end thereof and which are slidably mounted in guides 15 secured to the main frame 6. Air cylinders 16 are secured to the main frame 6 and have pistons 17 (Fig. 4) therein which are connected to the blocks 14 by piston rods 18. Each air cylinder 16 has ports 19 and 20 connected by air lines 21 and 22 to the valve 23 (Fig. 5). The valve 23 is connected by an air line 24 to a suitable source of compressed air supply. The valve is also equipped with an air exhaust pipe 25. A valve operating handle 26 is adapted to operate the valve to permit the compressed air to pass into the line 21 to force the pistons 17 down (Figs. 4 and 5) so that the periphery of the main ironing roller 13 will exert pressure against the ironing shoe 7 and at the same time the valve permits the air below the pistons in the cylinders 16 to be exhausted through the valve and its exhaust pipe 25. Moving the valve handle to the left (Fig. 5) will connect the supply line 24 and the line 22 to permit the compressed air to enter the cylinders 16 below the pistons. At the same time the line 21 will be connected to the exhaust pipe 25 to permit the air above the pistons in the cylinders 16 to be exhausted. This operation will raise the pistons to relieve the roller 13 from pressure upon and engagement with the shoe 7. A locking rod 27 extends through an opening in one of the guides 15 and is pivotally engaged with a lever 28 at 29 and the other end of the locking rod 27 extends beyond the lever 28 and is adjustably engaged with the handle 26. A coil spring 30 surrounds the locking rod 27 between the lever 28 and the handle 26 so that when the handle 26 is moved to the left (Fig. 5) the spring is compressed and the locking rod 27 is thereby urged to the left to engage the block 14 until the pistons raise the ironing roller so that an opening 31 in the block 14 becomes alined with the locking rod when the spring 30 forces the locking rod into the opening 31. The lever 28 is rigidly mounted on a rod 32 which extends across the machine and has as its other end a lever 33 mounted thereon and pivotally engaged with another locking rod 34 which operates in the same manner as the locking rod 27. When the locking rods 27 and 34 engage the openings in the blocks 14 the main ironing roller 13 is held up out of engagement with the ironing shoe 7 and in inoperative position when the air supply to the valve is shut off. When the handle 26 is moved to the

right (Fig. 1) after the air supply to the valve is turned on the handle engages adjusting nut 26' (Fig. 5) and thereby retracts locking rods 27 and 34 to disengage them from the blocks 14 where-
5 by the roller will drop down into engagement with the shoe 7.

A motor 35 is provided and is operatively connected to the ironing roller 13 through a gear box 36 and a driving chain 37. A belt 38 extends 10 around the ironing roller 13, between the roller and shoe 7, around the end of the ironing shoe having the steam chamber 9 located therein, around a roller 39, and around a conventional adjusting roller 40. A conventional belt tightening roller 41 is provided to keep the belt in proper 15 taut condition at all times. A discharge belt 42 extends from below the roller 39 to the right of the machine (Fig. 1). The belt 42 is driven from the gear box 36 through a gear 43 to move the 20 belt in the direction of the arrow (Fig. 1).

When the material to be ironed is admitted to this part of the machine it enters on the left side (Fig. 1) of the roller 13 between the belt 38 and the ironing shoe 7 and travels between the belt 25 38 and shoe 7 around the end of the shoe to the roller 39 where the material is dropped onto the belt 42 and carried out of the machine.

A suction pump 44 is operated by the motor 35 and is connected to the suction chambers 10, 11. 30 The suction chamber 10 is perforated on its face at 10' so that when the damp material being ironed passes thereover the steam generated therein by the heat from the ironing shoe is withdrawn from the material and is discharged 35 by the pump 44. The suction chamber 11 is perforated on its face at 11' to remove the steam generated in the material being ironed after the material has left the suction chamber 10. The back of the suction chamber 11 is perforated at 40 11'' so that when the material passes over the end of the ironing shoe having the steam chamber 9 located therein, the steam generated by this drying process may also be withdrawn from the material and be discharged by the pump. It 45 will thus be seen that while the damp material is being ironed the steam that is generated therein due to the heat of the ironing shoe will be removed from the material as it is generated. After the material has passed from beneath the 50 ironing roller the ironing shoe is still in contact with the material to thoroughly dry it after it is ironed and the steam generated at this point in the path of travel of the material will also be removed therefrom so that the material will be 55 thoroughly ironed and dried upon being discharged from the mangle.

My invention contemplates the use of and I prefer to use a preheating or preironing device which has the advantage of preparing the material to be ironed before it enters the main ironing mechanism of the machine, which has just been described, although the preheating device is not essential to the successful operation of the mangle. A sub-frame 45 may be mounted on 60 the main frame 6 at the front thereof to carry the preheating or preironing mechanism. This mechanism consists of another ironing shoe 46 which may or may not have suction chambers therein and which is rigidly mounted on the sub-frame, and an ironing roller 47 journaled in blocks 48 at either end thereof and which blocks are slidably mounted in guides 49 on the sub-frame. Air cylinders 50 similar to the cylinders 16 are provided to raise and lower the ironing 70 roller 47 into and out of engagement with the 75

ironing shoe 46. However, the pistons in these cylinders are raised to exert ironing pressure and lowered to remove the pressure and to accomplish this the air line 51 is connected to the air line 21 and the air line 52 is connected to the 5 air line 22. These connections provide that when the valve handle 26 is operated to raise the main ironing roller 13 the roller 47 will be lowered and when the handle 26 is operated to lower the main ironing roller 13 to exert ironing pressure 10 the roller 47 will be raised for the same purpose. A chain 53 operatively connects the ironing roller 47 with the gear 43 to operate the roller 47 in the direction of the arrow (Fig. 1). A small roller 54 is provided adjacent the periphery of 15 the ironing roller 47 and strings 55 pass thereabout and about the roller 47 as shown in Fig. 3 for a purpose hereinafter described. The sub-frame 41 also carries a feed belt 56 for feeding the material to be ironed to the bight between 20 the shoe 46 and roller 47 and is operated by a chain 57 connected to the gear 43 to move the belt in the direction of the arrow (Fig. 1). The material to be ironed is spread upon the feed belt 25 56 which feeds the material into the bight between the roller 47 and shoe 46. The material then passes partly around the roller and under the shoe 46 and is kept from sticking to the roller because of its dampness by the strings 55 which feed the material into the inclined end of the 30 shoe 7 for the main ironing operation as heretofore described.

The preheating mechanism is primarily for the purpose of partially drying out the material being ironed before it receives its main ironing operation between the ironing roller 13 and shoe 7 but it also partially irons the material so that the main ironing operation is facilitated to this extent. When the machine is desired placed out of operation the rollers 13 and 47 should be removed from contact with their respective shoes by operation of the air valve 23 so that the usual padding on the rollers will not become flattened or the belt or padding become scorched. The roller 13 is held from contact with its shoe by 45 means of the locking rods 27 and 34 and the roller 47 is held from contact with the shoe 46 by gravity when the air pressure is shut off at its source.

While I have illustrated and described a preferred form of construction for my invention, it is to be understood that this is capable of variation and modification and I therefore do not wish to be limited to the precise details set forth but desire to avail myself of such changes and 55 alterations as fall within the purview of the following claims.

I claim:

1. In a mangle having a main frame and an ironing roller mounted on said frame, an ironing shoe cooperatively engaging said roller and comprising a steam chamber for heating the shoe and a suction chamber having a perforated face coincidental with the face of the shoe and a perforated back coincidental with the back of the 65 shoe, means supplying steam to the steam chamber for heating said shoe, means for conducting the material being ironed across the perforations in the face and back of the shoe, and means producing suction in the suction chamber whereby 70 steam generated in the material being ironed during the ironing thereof is removed immediately therefrom and the material will be dried before leaving the mangle.

2. In a mangle having a main frame and an 75

ironing roller mounted on said frame, an ironing shoe comprising a pair of steam chambers for heating the shoe and a pair of suction chambers, one of said steam chambers extending from one 5 end of said shoe beyond the middle thereof and surrounding one of said suction chambers on three sides, the other of said steam chambers arranged at the other end of said shoe, and the other of said suction chambers interposed between 10 said steam chambers, said first mentioned suction chamber having a perforated face on the fourth side thereof coincidental with the face of the shoe and said other suction chamber having a perforated face coincidental with the face of the shoe and a perforated back coincidental with the back of the shoe, means supplying steam to 15 the steam chambers for heating said shoe, means for conducting the material being ironed across the perforations in the face and back of the shoe, and means producing suction in said suction chambers whereby the material being ironed will have the steam generated therein removed immediately therefrom through the perforations in the face of the suction chambers during the 20 ironing of said material and the material will be 25

dried by the heat from said other steam chamber and the steam generated in the material during the drying operation will be removed from the material through the perforations in the back of the shoe. 5

3. In a mangle, a main frame, an ironing shoe rigidly mounted on the frame, an ironing roller mounted on said frame for movement to and from said shoe, means for engaging the roller with said shoe in cooperative ironing relation thereto, an endless belt operated by said roller and passing between the roller and shoe, around one end of the shoe, and over the back of the shoe, said shoe comprising a steam chamber for heating the shoe and a suction chamber having a perforated face coincidental with the face of the shoe and a perforated back coincidental with the back of the shoe, means supplying steam to the steam chamber for heating said shoe, and means producing suction in the suction chamber whereby steam generated in the material being ironed during the ironing thereof is removed immediately therefrom and the material will be dried before leaving the mangle. 10 15 20 25
